CLAMSHELL BUCKET

Eric H. Lichtenberg, Milwaukee, Wis., assignor to
 The C. S. Johnson Company, Champaign, Ill., a
 corporation of Illinois

Application June 19, 1943, Serial No. 491,436

2 Claims. (Cl. 37—186)

The present invention pertains to improvements in clamshell buckets of the two-line type.

Generally stated, the object of the invention is to provide such a bucket in which provision is made for minimizing fouling, wear and breakage of the closing line.

Experience has shown that in such buckets failure of the closing line most frequently occurs due to kinking and fouling of this cable at its fair-lead on the bucket head. When the bucket is at rest, as, for example, on a pile of material, and the closing line is slackened off, a kink frequently forms in the latter at its fair-lead. Subsequent tensioning of the closing line, to close the jaws of the bucket and thus pick up a load, strains the line at the kink so that after continued use failure customarily occurs first at the point mentioned. The general object of the present invention is to overcome the difficulty outlined through the provision in the bucket of a swivel type fair-lead, coordinated in a novel manner with the other elements of the structure in such a way as to prevent kinking or fouling of the closing line.

In a more specific sense, the invention also resides in the provision of such a bucket with a swiveled fair-lead for the closing line and a coordinated novel guard arrangement for protecting the fair-lead mechanism when the bucket falls over on its side, as is frequently the case in ordinary use.

Further objects and advantages of the invention will become apparent as the following description proceeds, taken in connection with the accompanying drawings in which:

Figure 1 is a side elevation of a clamshell bucket embodying the present invention, the bucket being shown in closed position and the guard about the swiveled fair-lead being vertically sectioned to expose the interior arrangement of the parts.

Fig. 2 is an end elevation of the bucket of Fig. 1, with one of the hinges shown partially in longitudinal section.

Fig. 3 is a detail sectional view of the bearing structure incorporated in the swiveled fair-lead.

Fig. 4 is a side elevation of the bucket, but shown in its open position.

Figs. 5 and 6 are fragmentary plan views of the bucket, showing the swiveled fair-lead in respectively different angular positions therefor.

While the invention is susceptible of various modifications and alternative constructions, I have shown in the drawings and will herein describe in detail the preferred embodiment, but

it is to be understood that I do not thereby intend to limit the invention to the specific form disclosed, but intend to cover all modifications and alternative constructions falling within the spirit and scope of the invention as expressed in the appended claims:

Referring more particularly to the exemplary structure, the bucket shown comprises a bucket head 10 and a hinge head 11. Extending side-by-side through the latter is a pair of hinge pins 12, journaled within suitable bearings 13 in the hinge head as indicated in Fig. 2. Pinned to the outer ends of the hinge pins 12 are upstanding arms 14a of a pair of opposed scoops or shells 14. Removable counterweights 11a are mounted on the hinge head to assure proper opening of the bucket if desired. The bucket head 10 is of inverted box shape, being preferably comprised of plates welded together to form side walls 10a, end walls 10b, and a top wall 10c reenforced by gussets 10d. To the four corner portions of the bucket head 10 are pivotally connected the usual lever arms 15, which are pivotally connected at their opposite or lower ends to the respective outer corners of the scoops 14.

As to the two lines for the bucket, the hoist line 16 is secured by a clamp 17 carried by a clevis 18 on the bucket head 10, while the closing line 19 is reeved over closing sheaves 20, 21 attached, respectively, to the bucket head 10 and the hinge head 11. One end of the closing line 19 is anchored to the bucket head 10 at 22, while the other or free end of the closing line is led off to a suitably located winch or the like (not shown) for hauling in the same to pull the scoops 14 from the open position of Fig. 4 to the closed position of Fig. 1. The upper closing sheaves 20 are housed within the bucket head 10, being journaled between the side walls 10a of the latter, and the lower closing sheaves 21 are journaled in a support 23 fixed to the top of the hinge head 11.

To guide the so-called "standing part" of the closing line 19 as it leaves the closing sheaves 20, 21, and prevent kinking or fouling of the same, a special swivel type fair-lead, designated generally by the numeral 24, is provided on the bucket head 10. In the construction illustrated, this fair-lead comprises an annular support 25 having a central opening or throat 26 (see Fig. 3) through which the closing line 19 passes. This throat is bordered by an annular depending sleeve 25a integral with the support 25, and the latter also has at its perimeter a depending annular flange 25b. The sleeve 25a projects down

into a central opening in a plate 28 bolted to the top plate 10c of the bucket head which latter itself has a large central opening in it. A sleeve bearing 28a carried by the plate 28 journals the sleeve 25a and its attached support 25 for swiveling motion about a vertical axis passing through the center of the throat 26. Antifriction thrust bearings 30, 31 are disposed above and below the plate 28, the upper bearing being encircled by the retaining flange 25b in support 25 and the lower bearing being held in place by a cover 25c removably fixed to the lower end of sleeve 25a.

Between upstanding side plates 29 fixed to the support 25 is journaled a large diameter guide sheave, a complemental pair of such guide sheaves 27 being disposed in edge-to-edge relation on opposite sides of the throat 26 in the present instance and receiving the standing part of the closing line 19 between them. By using such large diameter guide sheaves, and swiveling them to remain in alignment with the closing line irrespective of the angle at which the latter is led from the bucket, kinking or twisting of the closing line is effectually prevented.

To cause the swiveled fair-lead 24 to always assume a position in which the guide sheaves 27 are aligned with the closing line 19, a pair of guides in the form of elongated rollers 32 are utilized. These rollers are journaled between the end plates 29a fixed between the ends of the plates 29. The rollers are revoluble about axes at right angles to those of the guide sheaves and are disposed on opposite sides of the projected center line of the throat 26. The longitudinal slot thus formed between the rollers 32 permits the standing part of the closing line 19 to be swung laterally through a wide angle in leading off the closing line to a desired point. Whenever the angle at which the closing line is led off is changed, however, so that it would otherwise tend to assume an angular position with respect to the slot between the rollers 32, its engagement with the one of the latter rollers across which it is pulled swings the swiveled fair-lead around until the slot between the rollers 32 is aligned with the closing line. Since such slot is aligned with the grooves in the peripheries of the guide sheaves 27, the latter are always maintained in substantially accurate alignment with the portion of the closing line leading from the bucket. As a result, the closing line always enters and leaves the guide sheaves 27 without any twisting or turning, so that there is no tendency for the same to kink, even though it be a heavy steel cable which is particularly subject to such difficulty.

Damage to the swiveled fair-lead 24 is prevented by an annular upstanding guard 33 welded to the top plate 10c of the bucket head 10. This guard extends in closely spaced and protective relation about the swiveling fair-lead structure so that both the swivel bearing and sheave bearings of the latter are protected from damage during use of the bucket. This is particularly important in the event that the bucket falls over on its side, as frequently happens when it is dropped on a pile of material. Not only are the parts of the fair-lead mechanism 24 protected against breakage, but of perhaps even more importance, when the bucket is lying on its side,

the fair-lead mechanism is free to swivel within the confines of the guard so that it is, even under such adverse conditions, maintained in proper alignment with the closing line 19.

The general mode of operation of the bucket will be clear from the foregoing. By way of brief recapitulation, it may be noted that the bucket is customarily lowered onto a pile of material by slackening away the hoist line 16 with the closing line 19 also slackened off, so that the bucket is lowered while in the open position of Fig. 3. Thereafter, the closing line 19 is drawn up, thus closing the scoops 14 to claw up a load of material. Then the hoist line 16 is reeled in to transport the loaded bucket to a desired point of delivery. At the latter point, opening of the bucket is accomplished by slackening off the closing line 19 so that the scoops 14 are permitted to swing apart again to discharge their contents. At all times the fair-lead mechanism is swiveled by coaction of the rollers 32 with the line, in the manner heretofore described, so that the guide sheaves 27 are always accurately aligned with the closing line. Consequently, fouling and kinking of the latter are effectually prevented even though the angle at which the closing line passes from the bucket to the operator station may vary widely during use.

I claim as my invention:

1. In a clamshell bucket, the combination with a bucket head and a hinge head having closing sheaves attached thereto and movable toward each other as a closing line reeved over the sheaves is tensioned, of a fair-lead swiveled on the bucket head for movement about an axis aligned with the standing part of the closing line leaving said sheaves, said fair-lead including a guide sheave disposed with its edge aligned with said axis to receive the standing part of the closing line, and a guard structure on the bucket head protectively surrounding said fair-lead.
2. A two-line clamshell bucket comprising, in combination, a hinge head having an opposed pair of scoops pivotally connected thereto, a bucket head having means thereon for attachment to a hoisting line, a pair of closing line sheaves connected, respectively, to said bucket head and hinge head and having a closing line reeved thereon, a fair-lead for the closing line comprising a support having a throat therein and a pair of sheaves journaled on said support in edge-to-edge relation on opposite sides of said throat to receive between them the closing line emerging through said throat from the closing sheaves, bearing means mounting said support for swiveling motion on said bucket head about a vertical axis passing through said throat, means for causing said support to swivel about said axis in a direction to bring said guide sheaves into alignment with the closing line irrespective of the angle at which the latter is led away from the bucket, said last-named means including an elongated pair of guide members mounted on said support above the guide sheaves and extending at right angles to the axes of the latter and disposed on opposite sides of the center line of said throat projected upward between said guide sheaves, and an annular upstanding guard on said bucket head surrounding said guide sheaves in protective spaced relation thereto.

ERIC H. LICHTENBERG.
